TIILT OUT CONTROL PANEL

Clement W. Alley, Lombard, Ill., assignor to Admiral Corporation, Chicago, Ill., a corporation of Delaware

Filed July 7, 1964, Ser. No. 80,746

Term of patent 7 years

(Cl. D56—4)

Fig. 1

Fig. 2

FIG. 1 is a perspective view of a tilt out control panel showing my new design.

FIG. 2 is an enlarged front elevational view.

FIG. 3 is an enlarged sectional view of the front face only of the control panel taken on the line 3—3 of FIG. 2.

FIG. 4 is an enlarged perspective view showing the control panel in a tilted down position.

FIG. 5 is an enlarged plan view of the control surface only seen in FIG. 4.

FIG. 6 is an enlarged sectional view taken on the line 6—6 of FIG. 5.

The dominant features of my design reside in those portions shown in full lines on the drawings, the dash-dot showings of a television receiver cabinet in FIG. 1 and of a portion thereof in FIG. 4 being for illustrative purposes only.

I claim:

The ornamental design for a tilt out control panel, as shown and described.
